Jean Causse, Millau, France

Application April 18, 1952, Serial No. 283,097

Claims priority, application France September 25, 1951

8 Claims. (Cl. 2—159)

This invention relates to a glove which has been specially designed for all kinds of manipulations and handlings in the course of which security requires a strong adherence between the hand and the manipulated part or the handled object. This glove will thus be used with advantage by automobile drivers, engine-drivers, persons manipulating fragile or dangerous objects, etc.

The glove according to the invention is mainly characterized by the fact that it comprises a plurality of suction-grip elements of resilient material which are placed at convenient points of the glove.

According to a presently preferred but not limitative embodiment, the invention may further comprise all or part of the following features:

(a) A series of suction-grip elements is placed in the part of the glove which straddles the palm of the hand and the base of the fingers.

(b) Further suction-grip elements are placed on the end joint of each finger, that is to say, on the second joint of the thumb and on the third joint of each other finger.

(c) The suction-grip elements of each series are solid with, and project from, a common base plate which is placed against the inside of the inner or palm face of the glove, the suction-grip elements being engaged into corresponding openings formed in said inner face of the glove, so that the adhering faces of said suction-grip elements are level with the external surface of said inner face of the glove.

The appended drawing represents by way of example an embodiment of the glove according to the invention.

Fig. 1 is a front view of the inner side of the glove.

Fig. 2 is a front view of a series of suction-grip elements solid with a common base plate.

Fig. 3 is a fragmentary section on line III—III of Fig. 1.

According to the shown embodiment of the invention the glove G, which is of leather, fabric or other suitable material, is provided on its inner or palm face 1 with a plurality of suction-grip elements each of which comprises a substantially cup-shaped body 2 of resilient material formed on its front face with a concavity 2a which ensures the suction-grip. These elements are thus adapted to adhere strongly to the part to be manipulated or to the object to be handled.

In the shown embodiment, a series A of suction-grip elements is distributed in two rows over the portion of the inner face of the glove which straddles the palm of the hand and the base of the fingers, while five further series comprising each two suction-grip elements are placed on the end joints of the five fingers, that is to say, on the second joint of the thumb and on the third joint of each other finger.

In each series, the suction-grip members of resilient material are preferably solid with a common base plate of the same material. The base plates are designated respectively by the references 3, 4¹, 4², 4³, 4⁴ and 4⁵.

Each base plate is placed against the inside of the inner face 1 of the glove and is secured thereto, for example by stitches (not shown). A lining 6 may further be provided in order to hold the base plate in position. The suction-grip elements 2—2a, which project from their base plate as shown on Fig. 3, are engaged into openings 5 formed in the inner face 1 of the glove, in such manner that the adhering faces of said suction-grip elements are level with the external surface of said inner face 1 of the glove.

2

It will be understood that the invention is not limited to the embodiment which has been described and shown and that it covers also any variations thereof which are based on the same principle and fall within the scope of the appended claims.

I claim:

1. A high adherence glove comprising a portion forming a covering for the palm of the hand, said glove portion being formed with openings, and a suction grip element placed in each of said openings, said suction grip element comprising a substantially cup-shaped resilient body having an adhering face formed with a concavity, said adhering face being level with the external surface of said glove portion.
10. 2. A high adherence glove comprising a portion forming a covering for the part of the hand which straddles the palm and the base of the fingers, said glove portion being formed with openings, and a suction grip element placed in each of said openings, said suction grip element comprising a substantially cup-shaped resilient body having an adhering face formed with a concavity, said adhering face being level with the external surface of said glove portion.
15. 3. A high adherence glove comprising glove portions forming coverings for the palm of the hand and for the inner sides of the fingers and thumb of the hand, said glove portions being formed with openings, and a suction grip element placed in each of said openings, said suction grip element comprising a substantially cup-shaped resilient body having an adhering face formed with a concavity, said adhering face being level with the external surface of said glove portions.
20. 4. A high adherence glove comprising glove portions forming coverings for the part of the hand which straddles the palm and the base of the fingers and for the inner sides of the fingers and thumb of the hand, said glove portions being formed with openings, and a suction grip element placed in each of said openings, said suction grip element comprising a substantially cup-shaped resilient body having an adhering face formed with a concavity, said adhering face being level with the external surface of said glove portions.
25. 5. A high adherence glove comprising a portion forming a covering for the palm of the hand, said glove portion being formed with openings, a base plate held against the inside of said glove portion, and suction grip elements projecting from said base plate, each of said suction grip elements comprising a substantially cup-shaped resilient body engaged into one of said openings, and having an adhering face formed with a concavity, said adhering face being level with the external surface of said glove portion.
30. 6. A high adherence glove comprising a portion forming a covering for the part of the hand which straddles the palm and the base of the fingers, said glove portion being formed with openings, a base plate held against the inside of said glove portion, and suction grip elements projecting from said base plate, each of said suction grip elements comprising a substantially cup-shaped resilient body engaged into one of said openings and having an adhering face formed with a concavity, said adhering face being level with the external surface of said glove portion.
35. 7. A high adherence glove comprising glove portions forming coverings for the palm of the hand and for the inner sides of the fingers and thumb of the hand, said glove portions being formed with openings, a base plate for each of said glove portions, each of said base plates being held against the inside of the corresponding glove portion, and suction grip elements projecting from each of said base plates, each of said suction grip elements comprising a substantially cup-shaped resilient body engaged into one of said openings and having an adhering face formed with a concavity, said adhering face being level with the external surface of said glove portions.
40. 8. A high adherence glove comprising glove portions forming coverings for the part of the hand which straddles the palm and the base of the fingers and for the inner sides of the fingers and thumb of the hand, said glove portions being formed with openings, a base plate for each

of said glove portions, each of said base plates being held against the inside of the corresponding glove portion, and suction grip elements projecting from each of said base plates, each of said suction grip elements comprising a substantially cup-shaped resilient body engaged into one of said openings and having an adhering face formed with a concavity, said adhering face being level with the external surface of said glove portions.
